APPARATUS FOR TREATING ARTIFICIAL
YARNSAlfredo Nai, Milan, Italy, assignor to "Chatillon"
Societa Anonima Italiana per le Fibre Tessili
Artificiali, Milan, ItalyApplication May 20, 1936, Serial No. 80,849
In Italy March 27, 1936

7 Claims. (Cl. 68—9)

The present invention relates to apparatus for washing, desulphurizing, bleaching and drying fibre bundles and artificial yarns in particular by passing the bundles through a liquid flowing 5 in a direction opposite to the movement of the bundles. The apparatus provides for frequent successive squeezings of the fibre bundles while immersed in the liquid so that the successive impregnations of the bundles is effected with fresh 10 liquid.

It has been ascertained that by providing some 15 suitably sloping channels of sufficient length and amplitude divided into sections of variable length at the end of which couples of diaphragms are placed which have the breadth of the channel and such height that the descending liquid may 20 overflow on them each diaphragm having an horizontal slot, the parallel fibres from the spinning machine entering from the lowest point and rising up to the highest parallel to the bottom of 25 the channel in opposite direction to the natural movement of the liquid, arrange themselves in the shape of a broad sliver which brushing with light friction alternatively the bottom and top sides of the slots of the successive diaphragms so 30 as to partially squeeze the fibres within the liquid appear at the exit of the various channels to be thoroughly washed, desulphurised, bleached, dyed, etc.

35 The invention will be described further in detail by way of example with reference to the accompanying drawings, in which:

Figure 1 is diagrammatical vertical longitudinal section on line I—I of Figure 2, and

35 Figure 2 is a diagrammatical plan view of Figure 1, showing a washing apparatus according to invention.

Fig. 2a is a partial modified view of the apparatus shown in Fig. 2.

40 Figure 3 is a view analogous to Figure 1 showing another form of apparatus in accordance with the invention.

Figure 4 shows, on larger scale, a detail of Figures 1 and 3.

45 Figure 5 represents a front view of one of the diaphragms shown in Figure 1, 2 or 3.

Figure 6 is a view analogous to Figure 4 showing another form of diaphragm, and

50 Figure 7 is a diagrammatical view of a system of treatment channels according to the invention.

Fig. 7a is a partial modified view of the apparatus shown in Fig. 7.

55 Referring to Figures 1-5, the pairs of diaphragms 2 situated in the channels 1 have a hori-

zontal slot 3 (Figures 4 and 5) through which, as said, the fibre bundle 4 is caused to pass. The said slot 3 is to be of suitable breadth and so chosen as to have the minimum linear density of fibres allowable with the breadth of the channel. Thus, for a channel of a breadth of 40-50 centimetres the breadth of the slot will be from 12 to 25 centimetres, and the height from 2 to 3 centimetres.

The diaphragms 2 of each pair are placed at a distance of 20-30 centimetres from each other so that the fibre bundle 4 will graze the lower horizontal side 3' of the slot 3 of the first diaphragm 2, and the upper horizontal side 3'' of the second diaphragm 2, or vice versa. In this manner the whole of the liquid conveyed by the fibres in their progress appears to be shifted from the lower part by the first slot 3, and for the upper part by the second slot 3, or vice versa. The sliver 4 then proceeds over each pair of diaphragms 2 impregnating itself with fresh liquid after having left nearly the whole of the liquid with which the fibre in the preceding section was impregnated.

Fig. 2a discloses a form of the invention where in the diaphragms are provided with slots which become increasingly larger from the lower end of the channel toward the upper end of the channel, with the exception of the uppermost diaphragm. Fig. 7a discloses a form of the invention wherein the diaphragms are arranged in pairs. The distance between the diaphragms of each pair increasing from the lower toward the upper end of the channel and also the distances between the pairs of diaphragms increasing from the lower to the upper end of the channel.

At the start of the operations the compartments 5 of channel 1 are filled with the liquid to be used in the various treatments, and immediately afterwards the liquids of each compartment will impregnate the fibres 4 in their progress. The latter are squeezed by the next pair of diaphragms 2 upwards and are re-impregnated with fresh liquid in the subsequent compartment 5, the channel 1 being continuously fed with fresh liquid through a pipe 6, and a constant outpouring of liquid from one compartment to the next lower one being obtained, and thus balanced concentrations are established in successive compartments, which vary with exponential law. Thus, suppose c to be the concentration in the lower compartment,

$\frac{c}{n}$

will be the concentration in the subsequent compartment,

$$\frac{c}{n^3}$$

- 5 that of the next following compartment, and so on. The value n is a function of the quantity of liquid fed on, its temperature, the breadth of the sliver and the breadth of the channel.
- 10 It has been furthermore observed that both the efficiency of washing and the eventual other treatments are greatly improved if the lengths of the channel sections limited by the pairs of diaphragms are increasing from the admission point 15 of the sliver towards the exit of same.

It is obvious, in fact, that the optimum condition of washing would be obtained if the fibres remaining immersed in the liquid could be isolated from each other because then each fibre 20 would be entirely surrounded by the liquid. This condition would, however, imply another condition, namely that the fibres are not to be subjected to tension. This, however, would engender the very serious drawback that a fibre, eventually ruptured in washing, would bend backwards thereby producing entanglement which would start breakage of all the other fibres.

In the system forming the subject matter of the invention the fibres appear to be subjected 30 to tension for preventing loss of the solidarity existing between them, which is such as to permit a fibre eventually broken to be carried away by the contiguous fibres. As the tension of the sliver owing to the resistance of the liquid is increasing from the lower to the upper part it is necessary for obtaining the same broadening in 35 all sections, that the length of the sections increase from the lower to the upper part. Thus also the breadth of the slots of the diaphragms, 40 is increasing in the same manner, excepting the slots of the outermost diaphragms which are smaller beyond which the sliver is led to the squeezing rollers.

The diaphragms 2 (Figures 1, 2, 3, 4 and 5) 45 may be of metal, glass, porcelain, ebonite, or the like.

Good results, both for the washing and the eventual other treatments of the sliver, are obtained by substituting for the diaphragms 2 (Figure 1) bars 8 of glass, porcelain or the like materials alternatively placed below and above the plane of the sliver 4, Figure 6, which the sliver brushes with slight friction.

Both in the case of diaphragms 2 and bars 8 55 the sliver 4 should brush the same only with slight friction in order not to break the fibres.

By using the above described devices with the channel designed for washing the sliver issuing from the spinning machine one obtains at the 60 exit of the said channel a yarn completely free from salts and perfectly neutral. During the progress of washing the acidity decreases in a more rapid way than the geometrical proportion and in the last compartments the water is perfectly neutral to the most sensitive indicators.

In order to eliminate the greatest possible proportion of the liquid impregnating the fibres, at the end of the washing channel a squeezing device is provided which may comprise a pair of 70 rollers pressed together, or better still especially for avoiding damaging the fibres, a device comprising roller 9 as shown in Figure 1. In order to ensure that the sliver remains open without there being superpositions of the second coil of sliver 75 over the first upper roller in the above described

squeezing device an inclined roller 10 is provided.

The squeezing rollers may be not only placed at the end of the channel but eventually also at one or more intermediate points as shown at 5 in Figure 2, so that the sliver besides being subjected to squeezing within the liquid by diaphragms or bars may also be subjected to another more intense squeezing before again coming into contact with the liquid. By the said intermediate squeezing the requirement of liquids used in the various treatments is materially reduced.

When the sliver is to be subjected to the successive treatments of desulphurising, bleaching, dyeing, etc., various channels of equal inclination are placed in series, each fed with suitable liquid, Figure 7. The sliver 4 after flowing through the first channel 1 and passing over a squeezing device 9, 10 enters a series of other channels 1', 1'', 1''' of variable length according to the treatment they are to be subjected to, the titre of sliver, the titre of unitary filament and temperature of bath, etc.

In each of the above described channels, either designed for washing or designed for the treatments with chemical reagents, the above described devices are placed in order to free the fibres gradually from water or from the solutions with which they are impregnated.

Besides being subjected to washing, desulphurising and bleaching the sliver may be subjected to dyeing in channels of the same type with suitable dyes. The process is particularly adapted for dyeing with sulphur dyes, because by the fact that sodium sulphide is used as desulphurising medium and sodium sulphide the sliver is also a component of the dyeing bath, the sliver already impregnated with this solution is passed directly to the dyeing bath without any intermediate washing or other treatment.

Example.—A bundle of fibres 4, having each a unitary titre of $1\frac{1}{2}$ deniers, or more, so as to form a sliver of a total titre of about 300,000 deniers, is caused to advance with a speed of from 60 to 100 meters per minute on the bottom of a channel 1 of a length of 20-60 meters, a breadth of 40-50 centimetres with an inclination of $2\frac{1}{2}$ per cent. fed in the highest part in the proportion of about 5-6 litres of hot or cold water, in which at a distance of from 2 to 6 meters pairs of diaphragms 2 are placed which are distant 20-30 centimetres from each other and have a slot 3 of a breadth of 12-25 centimetres through which the fibre bundle 4 is caused to pass in the above described manner. After the sliver has passed over the set of squeezing rollers 9, 10 desulphurising of the sliver is effected by washing in a second analogous channel of a length of 15-20 meters, whereupon it is washed in a channel of 20-60 meters, and then bleached, washed, dyed, etc. in channels of the same type but variable lengths.

In comparison with what is claimed in German patent, No. 508,983, all the operations of the process according to the present invention are carried out with the fibres held under tension thereby avoiding ruptures and entanglements which would be unavoidable if the said treatments were effected on yarns not under tension. Besides this by keeping the sliver under tension the eventually broken yarns are carried along with the sliver without producing entanglements or tufts.

All the main rollers of the squeezing devices are controlled by a sole transmission so that the peripheral speed is kept rigorously equal, and excessive tensions or slackenings are avoided.

5 The above described treatments may be used with artificial yarns of regenerated cellulose even if the said yarns are not designed for the production of short fibres. In this case the groups of filaments from the spinning machine 10 instead of being collected in a bundle may be kept distinct by suitable thread-guides, and collected at the end of the washing and other treatments, on suitable collecting devices, and then dried.

15 For the production of short fibre the sliver is cut by suitable devices after completion of said washing, bleaching and finishing operations.

Having now particularly described and ascertained the nature of my said invention and in 20 what manner the same is to be performed, I declare that what I claim is:

1. An apparatus for washing, desulphurizing, bleaching, dyeing and subjecting artificial yarn to finishing treatments comprising, a series of 25 independent compartments, inlet means and outlet means disposed at the respective ends of the compartment for a treating liquid, means for passing the yarn through the compartments in a direction opposite to the flow of the liquid, 30 diaphragms disposed at appropriate distances apart in the said compartment and transversely to the direction of movement of the yarn, said diaphragms being provided with smooth edges, the yarn contacting the said edges, and means for

tensioning the yarn to press the same against said edges whereby the liquid is expressed from the yarn while passing through the liquid in said compartments.

2. Apparatus as claimed in claim 1, in which 5 pairs of diaphragms are provided with slots to form the said edges and are so arranged that the yarn is compelled to brush with slight friction against the lower horizontal side of the slot of one diaphragm and the upper horizontal side 10 of the slot of the adjacent diaphragm.

3. Apparatus as claimed in claim 1, in which 15 said diaphragms consist of suitably spaced bars placed alternately above and below the path of travel of the yarn.

4. Apparatus as claimed in claim 1, in which 20 the diaphragms are arranged in equally spaced pairs and the distances between the diaphragms of each pair is constant throughout the length of the compartment.

5. Apparatus as claimed in claim 1, in which 25 the diaphragms are arranged in pairs, the distances between each pair of diaphragms and the diaphragms of each pair increasing from the outlet end to the inlet end of the compartment.

6. Apparatus as claimed in claim 1 in which 30 the length of the edges of the diaphragms is equal for all the diaphragms.

7. Apparatus as claimed in claim 1 in which 35 the length of the edges of the diaphragms increases from the outlet end to the inlet end of the compartment, excepting the outermost diaphragms of each compartment.

ALFREDO NAI.
